Des. 230,162

Patented Jan. 29, 1974

230,162

STAR ORNAMENT

Christina Fritsche, Cincinnati, Ohio, assignor to Cincinnati Milacron Inc., Cincinnati, Ohio

Filed Nov. 21, 1972, Ser. No. 308,482

Term of patent 7 years

Int. Cl. D11—05

U.S. Cl. D29—1 B

Fig. 2

Fig. 1

Fig. 3

FIG. 1 is a front elevational view of a star ornament showing my new design, the side opposite being identical thereto;

FIG. 2 is a top plan view; and

FIG. 3 is a bottom plan view.

I claim:

The ornamental design for a star ornament, substantially as shown and described.
